NONREFILLABLE CAN AND GREASE GUN

James P. Gentry, Jr., Cleveland, Ohio, assignor
to Halsey W. Taylor, Warren, Ohio

Application June 21, 1933, Serial No. 676,972

7 Claims. (Cl. 221—47.3)

My invention relates to grease cans or containers for supplying grease to a grease gun.

The general object of the invention is to provide an exchangeable non-refillable grease can 5 which can be readily attached to the grease gun and from which can the grease is automatically supplied to the grease gun and discharged therefrom when the gun is actuated.

Other objects and advantages of the invention 10 will be apparent as the specification is considered in connection with the accompanying drawings, in which:

Figure 1 is a longitudinal vertical sectional view through a grease gun having an interchangeable 15 grease container attached thereto, the air pressure operating mechanism being shown in action;

Figure 2 is a cross sectional view through the grease gun shown in Figure 1, the section being taken on line 2—2 of Figure 1;

20 Figure 3 is a plan view of the interchangeable fully sealed grease container;

Figure 4 is a longitudinal sectional view of the grease container, the section being taken on line 4—4 of Figure 3;

25 Figure 5 is an enlarged fragmentary sectional view through the scored top lid of the container showing the disk portion of said lid partly pried open;

Figure 6 is an enlarged sectional view on line 30 6—6 of Figure 7;

Figure 7 is an enlarged sectional view through the air controlling mechanism of the grease gun; and

Figure 8 is an enlarged sectional view through 35 the suction piston arrangement of the grease gun.

Referring more particularly to the drawings 1 denotes a metal can adapted to contain grease 2 or other lubricant for greasing automobiles and the like. The can is closed at top and bottom 40 by a lid and bottom member 3 and 4 respectively. Beneath the lid member 3 and resting on top of the grease 2 is a follower piston 5 consisting of a corrugated metal disk 6, superimposed upon and glued to a disk shaped washer 7 45 of felt or other suitable material. These piston parts are provided with centrally disposed registering openings 8 and 9 respectively, and the metal disk 6 is provided with an upstanding flange 10 surrounding the opening 8. The cover member 3 is heavily scored at 9' to permit ready removal of the disk portion 11 from the cover, by means of a pointed instrument, not shown.

After disk 11 has been pried loose and removed 50 the can is clamped to a screw threaded head 55 12 closing the rear end of the cylinder 13 of

grease gun 14, by means of a set screw 15, which screw bears against the free end of a split clamping ring 16 seated within a groove 17. However, it will be understood that any desirable means may be employed to connect the can to the gun. A grease conducting tube 18 extends through the registering openings 8 and 9 in the follower piston 5 and into the body of grease 2. Slidably mounted on this tube 18 is a sealing ring 19 which seats against the upstanding flange 10, a coil spring 20 being seated at opposite ends against the cylinder head 12, and the ring holds the latter to its seat and causes the follower piston 5 to keep the grease compressed into a compact mass and also prevents air being sucked into the grease below the 15 said follower piston and finally into the grease gun. That end of the tube 18 which extends into the body of grease in can 1 is normally closed by a ball valve 21 pressed to its seat by a coil spring 22. The piston 23 for cylinder 13 is fixedly 20 mounted upon a hollow piston and guiding rod 24 which extends at opposite ends through the cylinder heads 12 and 12' which also serve as stuffing boxes. The rear end of hollow rod 24 on which a small piston 25 is fixedly mounted, extends 25 within the bore 26 of tube 18, and in spaced relation to the wall of said bore, and is normally closed by a spring pressed ball valve 27. Bore 26 communicates at its inner end through a passage 30 43 with the open air to permit free reciprocatory movements of piston 25 in said bore during operation of the gun.

The operation of the grease gun is as follows: The pressure of spring 20 exerted against piston 5 has the tendency to force grease through 35 ball check valve 21 into the enlarged lower end of bore 26 of tube 18. However this flow of grease is primarily induced by the suction action of piston 25 when the latter is moving in a forward direction under the influence of air directed against the rear side of piston 23. Movement of the trigger 28 of grease gun 14 to the right and to the position shown in Figure 1 causes a spring 40 pressed slide valve 29 to bring about communication between a passage 30 and a chamber 40 and to move valve 31 from its seat against the tension of coil spring 32. Air from a pressure tank not shown, will now pass through said chamber 40 and passages 30 and 33 into cylinder 13 at the rear side of piston 23, causing the latter to move forwardly and a charge of grease to be taken into the end of the tube. At the same time the air pressure existing in the fore part of cylinder 13 is exhausted through passage 34 which passage 50 55 is brought into communication with the exhaust

passage 41 by the trigger movement just described. During the forward movements of pistons 23 and 25 ball check valves 27 and 35 at opposite ends of the hollow rod 24 are closed. The trigger 28 is then released and passage 30 is brought into communication with the exhaust passage 41, whereas passage 34 is brought into open communication with chamber 40, having a charge of compressed air therein. This air under pressure is passed through passage 34 to the forward side of piston 23 and the latter is caused to return to the rear end of cylinder 13, and at the same time returning piston 25 to the rear end of bore 26 of tube 18. Air from the rear end of cylinder 13 is at this time exhausted through passages 30 and exhaust passage 41. The charge of grease previously taken into the rear end of tube 18 through check valve 21 is thus forced through ball valve 27 into and through the hollow rod 24 and thence out through check valve 35 at the forward end of said rod into cylinder 36 where it is held by check valve 37. On the next forward movement of piston 23 and its hollow rod 24, caused by manual actuation of trigger 28, the grease in cylinder 36 is discharged through valve 37 and into and from outlet nozzle 38, the forward end of rod 24 acting as a ram in displacing the grease in cylinder 36 during this movement.

Inwardly extending ridges of other obstructions 39, formed in the interior of can 1, cooperate with the circumferential edge of the flanged portion of metal disk 6 in preventing return movement of piston 5 toward the open end of the can and consequently it will be practically impossible for a dishonest attendant to refill the can or substitute the grease in the can for an inferior grade of grease. Furthermore the lid 3, which always remains in place and offers a serious obstacle to a person tampering with or attempting destruction and removal of the piston for the purpose of refilling and substitution of another follower piston. The grease manufacturer as well as the service station owner and the public are thus protected against fraudulent substitution. The cans 1 may if desired bear the label of the grease manufacturer or the retailer if desired.

Having thus described my invention.

What I claim is:

1. The combination of a grease gun embodying means for compressing and discharging grease and means for actuating said first means, with a grease container interchangeably secured to and carried by said grease gun and means extended from said gun into said container adapted to suck grease from said container and force said grease directly into said compressing and discharging means, the means extended into said container being coupled with and operated by said actuating means.
2. The combination of a grease gun embodying reciprocatory means for compressing and dis-

charging grease and reciprocatory means for actuating said first means, with a grease container interchangeably secured to and carried by said grease gun, means extended from said gun into said container and reciprocatory means within said last means coupled with and operated by said actuating means and adapted to suck grease from said container and force said grease directly into said compressing and discharging means.

3. The combination of a grease gun embodying a ram for compressing and discharging grease, a reciprocatory piston coupled with said ram for actuating same, and means for reciprocating said piston, with a grease container interchangeably secured to and carried by said grease gun in axial alignment with said piston and a suction pump extended from said gun into said container and coupled with said piston for sucking grease from said container and forcing same into said ram.

4. The combination of a grease gun embodying a ram for compressing and discharging grease, a reciprocatory piston coupled with said ram, and means for actuating said piston, with a grease container interchangeably secured to and carried by said grease gun in axial alignment with said piston; a suction pump extended from said gun into said container coupled with said piston and communicating through a valve passage with said ram; shiftable means within said container adapted to pack said grease and yielding means to effect packing of the grease within said container by said shiftable means.

5. The combination described in claim 4 wherein the shiftable means consist of a stiffened follower member tightly engaged with the circumferential wall of said can.

6. The combination of a grease gun having a cylinder and piston, a hollow piston rod extending through and coupled with said piston, means for conducting air alternately to opposite sides of said piston for actuating said rod, a small piston on the rear end of said rod, a grease can interchangeably secured to said grease gun in alignment with said piston rod, said can being closed at its bottom and having a piston formed with an aperture registering with the rear end of said piston rod, a grease tube connected to said grease gun in axial alignment with said piston rod forming a cylinder for the piston at the rear end of said rod and extending into said can and through said piston, said rod when reciprocated by said piston causing the piston at the rear of said rod to draw grease from said can into said grease gun.

7. The combination described in claim 6 wherein the sides of the can are slightly indented to render difficult a return movement of the follower piston towards the top of the can.

JAMES P. GENTRY, JR.
